UNITED STATES PATENT OFFICE.

FRANK C. BALL AND EDMUND B. BALL, OF BUFFALO, NEW YORK.

DESIGN FOR A CASING FOR GLASS OIL-CANS.

SPECIFICATION forming part of Design No. 13,806, dated March 27, 1883.

Application filed February 19, 1883. Term of patent 3½ years.

To all whom it may concern:

Be it known that we, FRANK C. BALL and EDMUND B. BALL, both of Buffalo, in the county of Erie and State of New York, have 5 originated and invented a new and useful Design for Casings for Glass Oil-Cans; and we do hereby declare that the following is a full, clear, and exact description thereof, reference being had to the accompanying drawings, 10 forming a part of this specification.

In the drawings, Figure 1 is a front elevation of an oil-can, showing the principal panel of our improved design; and Fig. 2 is a side elevation of the same, showing one of the two 15 remaining panels, which two panels are similar in configuration.

Referring to the drawings, *a* is the style of glass can to which our improved casing is applied. *a'* is the cover. *a²* is an air-vent in the 20 same. *a³* is the spout, and *a⁴* is the handle.

The casing, of sheet metal, upon which our improved design is stamped surrounds the body portion of the can, and is ornamented substantially as follows: A narrow convex or 25 angular band, *b*, passes circumferentially around the casing at or near its upper portion, another and similar band, *b'*, passes around the center portion, and still another, *b²*, around the lower portion. The surface of the casing 30 is divided into three panels, of which *c* is the main panel, (shown full in Fig. 1,) and *c' c'* are the side panels, one of which is shown full in Fig. 2. As will be seen, these panels are centrally divided by the convex band *b'*. The 35 main panel *c* is separated from the side panels, *c' c'*, both above and below the central convex band, *b'*, by the narrow vertical raised portions *d*, which consist of a fluted central portion, *d'*, surrounded by a raised convex border, *d²*. These raised portions *d* do not extend quite to the convex bands *b b' b²*. The 40 two side panels, *c' c'*, are separated from each other, as clearly shown in Fig. 2, by a vertical opening, *E*, in the casing, extending from band *b* to band *b²*. The central portion of the 45 main panel *c*, just above and below the central band, *b'*, is ornamented with a series, *f*, of raised figures, both pyramidal and convex, of any fanciful design, which are arranged ra-

dially around the central figures, *f'*, the whole 50 figure presenting the appearance of having been divided and pushed apart by the central convex band, *b'*. The converging figures *f* may be varied to suit the fancy, and need not be confined to the arbitrary forms herein 55 shown, except that they must be made to converge to a common center to conform to the general features of our improved design. The blank space above and below the central design, *f*, is intended for any suitable words with 60 which to designate the peculiar form of casing. The side panels, *c' c'*, have their central portions decorated alike with the converging figures *g*. These figures have the same general arrangement as those of the main panel *c*; 65 but are herein shown, by preference, as slightly varied in detail. They may, however, be a reproduction of the figures in the main panel *c* without departing from the general features of our design.

We have herein shown corner and side figures, *h*, in the three panels of the casing, which may or may not be added without affecting the general appearance of our design, the leading features of which are the circumferential 75 bands *b b' b²*, the main panel *c*, the two side panels, *c' c'*, the fluted vertical portions *d*, and the central groups of converging figures, *f* and *g*.

We claim—

The design for metallic casings for glass oil-cans, consisting essentially of the raised circumferential bands *b b' b²* around the top, central, and bottom portions of the casing, the centrally-divided panels consisting of the main 85 panel *c* and the two side panels, *c' c'*, the vertical fluted raised portions *d* between the panels, and the divided converging figures *f* and *g*, located in the central portions of the panels, substantially as shown and described.

In testimony that we claim the foregoing as our own we affix our signatures in presence of two witnesses.

FRANK C. BALL.
EDMUND B. BALL.
